(57) **CLAIM**

The ornamental design for scissors as shown and described.

DESCRIPTION

FIG. 1 is a perspective view of scissors according to our new design;

FIG. 2 is a front elevation view thereof;

FIG. 3 is a rear elevation view thereof;

FIG. 4 is a right-side elevation view thereof;

FIG. 5 is a left-side elevation view thereof;

FIG. 6 is a top plan view thereof;

FIG. 7 is a bottom plan view thereof; and,

FIG. 8 is a bottom-perspective view thereof.

The broken lines shown in the drawings depict portions of the scissors that form no part of the claimed design.

1 Claim, 8 Drawing Sheets
